(57) **CLAIM**

The ornamental design for a trash can liner retainer, as shown and described.

DESCRIPTION

FIG. 1 is a front, left and top perspective view of a trash can liner retainer showing my design.

FIG. 2 is a rear, right and bottom perspective view thereof.

FIG. 3 is a front elevational view thereof.

FIG. 4 is a rear elevational view thereof.

FIG. 5 is a left side view thereof.

FIG. 6 is a right side view thereof.

FIG. 7 is a top plan view thereof.

FIG. 8 is a bottom plan view thereof.

FIG. 9 is a partial enlarged view of an area labeled **9** in FIG. 1; and,

FIG. 10 is a partial enlarged view of an area labeled **10** in FIG. 2.

The broken lines in the drawings depict portions of the trash can liner retainer that form no part of the claimed design. The dot-dash broken lines in the drawings are for the purpose of illustrating the enlarged view indicators and form no part of the claimed design.

1 Claim, 10 Drawing Sheets
